UNITED STATES PATENT OFFICE.

MARTIN NYSTROM, OF CHICAGO, ILLINOIS, ASSIGNOR TO THE BRUNSWICK-BALKE-COLLENDER COMPANY, OF WILMINGTON, DELAWARE, A CORPORATION OF DELAWARE.

DESIGN FOR A CABINET FOR A SOUND-REPRODUCING MACHINE.

Application filed October 13, 1924. Serial No. 11,057. Term of patent 7 years.

To all whom it may concern:

Be it known that I, MARTIN NYSTROM, a citizen of the United States, residing at Chicago, in the county of Cook and State of Illinois, have invented a new, original, and ornamental Design for Cabinets for Sound-Reproducing Machines, of which the following is a specification, reference being had to the accompanying drawing, forming a part thereof, in which—

Figure 1 is a perspective view showing the cabinet open and

Figure 2 is a similar view showing the cabinet closed.

I claim:

The ornamental design for a cabinet for a sound reproducing machine as shown.

MARTIN NYSTROM.
